UNITED STATES PATENT OFFICE.

FRANK D. ENNEY, OF CHARLESTON, WEST VIRGINIA.

CONVEYING APPARATUS.

Application filed September 15, 1924. Serial No. 737,933.

This invention relates to conveyer mechanism generally, and more particularly to conveyer mechanism for handling coal, earth, or rock discharged from mining or excavating machinery, in coal mines or in general excavating operations. Conveying apparatus is particularly desirable for use in coal mining in connection with continuously operating coal cutters in order to convey the cut coal from the movable cutting and charging machine to a stationary device used to load the coal into cars for removal from the mine. For this purpose a continuously extensible type of conveyer is most desirable in order to allow the uninterrupted forward movement of the cutting machine throughout a day's run.

It is a general object of this invention to provide a novel and improved conveyer mechanism of the extensible type.

More particularly, it is an object of this invention to provide an extensible conveyer mechanism, the length of which may be so adjusted that, when used in connection with mining or excavating machinery, the material cut may be conveyed from the machine continuously to a fixed discharge point, notwithstanding the advance of the machine in the cutting operation.

Another object of this invention consists in the provision of a novel conveying apparatus wherein two endless belt type conveyers are arranged one above the other, both running in the same direction, the uppermost one being adapted to discharge upon the lower one and being longitudinally adjustable in respect thereto, one portion of the conveyer being provided with charging mechanism and the other portion with adjustable discharging mechanism for loading cars, etc.

It is still a further object of this invention to provide a novel form of extensible conveyer including a stationary framework carrying a belt type conveyer and a movable framework carrying a belt type conveyer, both of said conveyers running in the same direction, the movable one being located above and adapted to discharge onto the lower one, means being provided to adjust the overlap of the two conveyers to regulate the distance between the charging and discharging ends of the mechanism, and additional means being provided for the convenient extension of the stationary portion

of the conveyer in order to increase the range of the mechanism.

For an understanding of this invention, reference should be had to the following specification taken together with the accompanying drawings wherein are disclosed several embodiments of the invention for the purpose of illustrating the manner of carrying the same into effect, with the understanding that various modifications and changes may be made in the various parts and their associations without departing from the scope of the invention.

In said drawings:

Figure 1 is a side elevation of the stationary part of a conveyer constructed according to this invention and including a discharge loading mechanism;

Figure 2 is a side elevation of the movable portion of the conveyer showing one form of charging device, the forward end of the stationary portion being shown in cooperation with the movable portion;

Figure 3 is a transverse section on line 3—3 of Figure 2 showing means for extending the stationary portion of the conveyer;

Figure 4 is a transverse vertical section on the line 4—4 of Figure 2 showing the means of mounting and supporting the movable portion of the conveyer;

Figure 5 is a side elevation of the overlapping portions of the stationary and movable parts of a conveyer showing a modified manner of supporting the movable portion;

Figure 6 is a transverse vertical section on line 6—6 of Figure 5;

Figure 7 is a plan view of the forward or charging end of the movable portion of a conveyer showing in conjunction therewith a pair of wing type conveyers for use in hand loading;

Figure 8 is an end elevation of Figure 7;

Figure 9 is a vertical section on line 9—9 of Figure 7;

Figure 10 is a vertical section on line 10—10 of Figure 7; and

Figure 11 is a detail on an enlarged scale.

Referring particularly to Figure 1, there is disclosed at A a movable boom type of discharge apparatus for loading cars, and at B a known type of coal cutting machine which is adapted to move forward under its own power into the tunnel cut by itself in order to keep its cutters against the face of the coal. For the purpose of connecting

the stationary discharge device A with the movable cutting device B, it is necessary to provide some form of extensible conveyer mechanism for conveniently transporting the coal from the device B to the device A. For this purpose, there is provided a pair of traveling belt conveyers C and D, the conveyer C resting upon the ground or the floor of the mine and being directly connected to the discharge mechanism A, while the conveyer D is adapted to be supported in any suitable manner above the conveyer C being directly connected to and adapted to move with the cutting and charging mechanism B. The conveyer D overlaps the conveyer C and both belts run in the same direction in order that material on the belt D on reaching the end thereof will be discharged upon the belt of the conveyer C to be carried to the discharging mechanism.

The conveyer C comprises a framework composed of four parallel and longitudinally extending bars 10, 11, 12 and 13 arranged upon the four edges of a rectangular prism. The upper and lower members on each side of the frame are connected together at intervals by means of the vertical plates 14 overlapping the longitudinal bars and being fastened thereto in any suitable manner such as by riveting, welding or bolting. The plates 14 on opposite sides of the framework are exactly opposite each other and each pair thereof provide support for two transversely extending cylindrical rods 15 and 16, providing axles upon which the rollers 17 and 18 are journaled. It may sometimes be preferable to provide solid side members, such as steel plates, which may take the place of the longitudinal members 10, 11, 12 and 13 and the vertical members 14, thus forming a framework comprising two parallel side members connected together by the axles of the rollers. Such a construction will better serve to protect the belt from slate falls or from coal thrown against it by blasts.

The uppermost rollers 17 may be of any suitable type to support the traveling belt 19, and as shown in the figure are preferably of the troughing type having the parallel central section 20 and the conical ends 21 in order to cause the belt to assume the form of a trough as is well known, for the purpose of preventing the conveyed material from falling off of the edges of the belt. The return or idler pulleys 18 may be of any desired type, here shown as plain parallel cylinders. Bosses 22 are formed integral with the vertical plates 14 in order to provide thickened sections to retain and support the shafts 15 and 16 and also to limit the amount of longitudinal movement of the rollers.

The shafts 16 are extended a considerable distance beyond the outer faces of the plates

14 in order to provide axles upon which are mounted wheels 23 adapted to support the conveyer mechanism and to allow it to be readily moved in a longitudinal direction when desirable.

In order that the conveyer mechanism may be readily transported, it is made of as light construction as possible consistent with strength, and in order to provide additional support against buckling due to the weight of material on the belt, means are provided at the forward and rearward ends of the stationary portion C to place it under longitudinal tension. Such means may conveniently be, at the forward end, a pair of mine jacks such as 24 fastened, as is well known, between the floor and the ceiling of the mine tunnel and connected to the reduced forward end of the stationary portion C by means of the pins 25. The rearward end of the framework C is connected to the stationary discharge mechanism A by means of the boat jacks 26, one connected to each of the members 10, 11, 12 and 13. These jacks are in the nature of large turnbuckles having ratchet handles whereby considerable longitudinal tension may be applied throughout the length of the conveyer mechanism in order to retain it rigid and in a straight line.

The belt 19 passes over the large head pulley 27 at the forward end of the stationary conveyer and at the rearward end is elevated where the framework members diverge as shown at 28, and passes over the idler pulley 29 and the tail pulley 30 at the discharge end from whence it passes partially around the drive wheel 31 and the snub pulley 32, which may be provided with weights or springs to maintain a proper tension on the belt, and is returned along the idler rollers 18. The tail pulley 30 is mounted on a loading beam which can be raised or lowered as desired in order to discharge the conveyed material into the car or other device such as shown at 33.

The electric motor 34 drives the drive wheel 31 by means of the worm and worm wheel mechanism shown at 35, the position of the snub pulley 32 being adjustable to vary the tension on the belt.

The upper bars 10 and 11 of the stationary conveyer system project slightly above the upper ends of the vertical spacers 14 and form rails upon which grooved wheels carrying the movable conveyer system are adapted to travel. This movable conveyer system comprises a conveyer frame substantially identical in structure with either type of the lower frame, shown as having side rails or bars 10', 11', 12' and 13' and the vertical space plates 14' connecting the two bars on either side of the framework. Axles 15' and 16' serve to carry the troughing rollers 20' and the idler rollers 18'. Instead of the wheels 23, the extensions of the axles 16'

are provided with the wheels 23' grooved as at 36 to fit over the side rails 10 and 11 of the lower conveyer frame. It will be understood that the belt 19' of the upper conveyer frame is adapted to travel in the same direction, as shown by the arrows, as the belt 19 in the lower conveyer frame in order that material discharged from the upper belt will be carried by the lower belt to the discharge mechanism.

Any suitable mechanism may be provided at the charging end of the movable conveyer system. In Figure 2 there is disclosed, by way of example, only, a coal cutting machine rigidly attached to the conveyer frame and comprising a crib 37 supported by the wheels 38 adapted to run on the floor of a mine. A pair of parallel shafts 39 carry at their forward ends the cutters 40 adapted to be rotated in opposite directions by means of the cross shaft 41 to which they are connected by means of the worm and worm wheel drives 42. The cross shaft 40 is driven from the electric motor 43 by means of the worm and worm wheel 44 or any other suitable drive. The direction of rotation of the cutters 40 is such that they advance toward each other at the bottom and thus serve to scoop up the coal which they have already cut and pass it onto the belt 19' which extends from the conveyer frame over the idler pulleys 45 to the head pulley 46 spaced closely adjacent to the cutters and being driven by suitable gearing (not shown) from the motor 43. Any of the well known means for advancing the coal cutting mechanism may be used, it being noted that the machine is always free to travel forward carrying with it the upper conveyer mechanism to the extent of the overlap of the two conveyer systems. It is found desirable to provide sufficient length to the upper conveyer frame to allow for one day's running of the coal cutter, after which it may be necessary to lengthen the stationary framework if it is not found desirable to move the track upon which the cars 33 travel.

In order to provide for the ready lengthening of the stationary conveyer framework, the four longitudinal bars or the plates forming the framework are each made in two sections which overlap as shown at 47 in Figure 2, and which is clearly illustrated in the cross section Figure 3. Each of the overlapping sections is provided with a series of transverse holes, pairs of which may be brought into register and pins inserted to maintain the frame rigid. At the end of a day's run, when it is desirable to lengthen the stationary framework, these pins may be withdrawn, the belt disconnected and the forward end of the framework rolled on its rollers to a position where its foremost end is substantially against the rear of the crib 37. The belt may now be pieced to the

proper length and the framework extended to place it under sufficient tension to lift the snub pulley, the pins then being placed in registering holes in the frame, after which the mine jacks 24 are fastened in position and tension applied to the frame by means of the boat jacks 26. It will be obvious that any desirable length of the stationary framework may be obtained by the addition of extra sections and that the amount of overlap between the upper and lower frameworks may be any desired amount to accommodate the speed of movement of the charging device.

Figures 5 and 6 disclose a slight modification of the conveying system just disclosed, the stationary portion being a substantial duplicate of that shown in Figures 1 to 4, inclusive. The movable portion may be provided with any form of loading mechanism, either that shown in Figure 2 or any other, and it is adapted to be moved and adjusted longitudinally in respect to the lower portion by being rolled on the wheels 50 which are mounted upon the axles 51 carried in the bosses 52 upon extensions of the vertical spacing plates 14². Guide members 53 of L-shape project downward from the axles and at their inner ends cooperate with the outer faces of the vertical space plates 14² on the bottom framework to maintain the two frameworks in proper alignment. The mode of operation is in every respect the same as in the previously described modification, but it is sometimes found that owing to the roughness or unevenness of the floor, better operation can be obtained by use of the large wheels. Moving of the upper conveyer and the coal cutter is also facilitated.

In Figures 7 to 11 is disclosed a modification in which means are provided to accommodate hand charging in connection with the traveling belt which is particularly desirable for use in low veins of coal where it would be found necessary under present mining conditions to remove either the roof or floor to make sufficient head room. In this system, the lower or stationary framework is substantially identical with that described in the two previous modifications, but being shown with the sides formed of solid plates 54. The upper framework as shown is formed of the solid side plates 55, adapted to roll on the top edges of the plates 54 by means of the rollers 56 carried thereby. The outer end of the upper section is widened so that its lower edge is in the same plane as the lower edge of the lower section, and this portion is provided with the wheels 57 adapted to run on the floor of the mine.

Upon either side of the forward end of the movable section are mounted the wing sections 58. These sections include the side plates 59 with the enlarged inner and outer

end portions 60 and 61 which are held together in a similar manner to those of the main portion of the conveyer, that is, by the transverse axles for the troughing and idler rollers. The belt on the upper or movable section of the conveyer runs as usual over the troughing rollers 62 and the idler rollers 63, but at the widened portion 64 slopes downwardly, as shown best in Figure 9, and 5 the upper reach thereof passes beneath the rollers 65 which cause it to run horizontally. The belt then returns around the head pulley 66 carried in the extension 67 of the widened portion, from whence it returns over 10 the usual idlers 63. Each of the wing conveyers 58 is provided with a belt, as shown, running over the upper or troughing rollers 68 and the return idler 69. At the outer end of these wing sections are the head 15 pulleys 70 with means 71 for adjusting the tension of the belt. The belts incline upwardly toward the center and pass over the discharge pulleys 72 which are closely adjacent to the horizontal portion of the upper 20 conveyer belt which is defined by the rollers 65. Guides 73 are provided in order that coal passing over the discharge pulleys 72 may be guided out toward the center of the belt on the upper or movable conveyer section. 25

The wing belts may be driven in any suitable manner. Where they are both quite long, it may be best to drive them with an independent motor, driving the upper or 30 movable section of the belt from the same motor, since with a wide front such as caused by the large wing sections, the forward movement in one day will be quite small, and hence the movable section will be short and 35 the belt can readily be driven from the wing belt drive. Where, however, the wing belts are fairly short, it may be found desirable to drive them with one motor and the belt of the movable section with another, since 40 it will be somewhat longer to take care of a day's run.

By the use of a device as described in this modification, it will be apparent that miners 45 removing coal by hand can shovel it on the traveling wing belts and it will be carried to the main belt of the movable section and then transferred to the main belt of the stationary conveyer frame and finally discharged by means of the loading device in 50 to the cars. Since the height of the whole mechanism is not great, it is apparent that 55 it may be used when working very low veins of coal without necessitating the removal of roofing or flooring for head room as with 60 the usual car type of conveyer. Since the wide front of this wing type conveyer will, of necessity, move forward very slowly, the 65 movable portion of the framework which overlaps the stationary framework need be 70 quite short.

The wing belts move inward toward the main belt and are adapted to be loaded by hand, the miners standing in front of the wing sections are shovelling the coal thereon. In order to prevent the coal from being 75 thrown over the belts, that is, beyond the wing sections, the side extensions 74 are provided which comprise the plates, best shown in Figure 10, curved in transverse section 80 overlapping the belt and provided with the stiffening bars 75 projecting vertically downward therefrom as shown at 76 and being held by the straps 77 on the side plates 59, from which they may be readily removed when desired. In Figure 10 a transverse 85 view of a wing section is shown. It is clear from this view that the solid side plates 59 are provided with the bosses 78 to better support the axles for the troughing rollers 68 and the idler rollers 69. The idler rollers 90 may be pipe sections provided with ball bearings at their ends in order that they may more readily rotate on their axles. The troughing rollers may consist of a central pipe section 79 having at its ends ball or 95 other suitable bearings and the three conical sections 80, 81 and 82 at each end thereof, progressively increasing in size, and each having independent bearings on the axle in order that the parts may rotate at different speeds due to their different diameters and the constant belt speed.

By making the side members of the various conveyer portions of solid steel plates, 100 holes may be drilled in different portions in order that changes may be readily made in the location and spacing of the idler and troughing rollers or the head pulleys, etc., to adapt the conveyers for different uses, and it will thus be evident that extreme convenience is provided by this construction and the 105 fewest number of parts consistent with economy are provided for a large variety of conveyer types.

From the above description and drawings, 110 it will be clear that this invention contemplates a material improvement in conveyers, especially those for use in coal or other mines. The machines are also particularly 115 adapted for use with entry driving machinery, loading or tunneling machines or for any other apparatus where it is desirable to keep the charging end of the conveyer up to the working point at all times without moving the discharge end.

This invention has been particularly described for use in conjunction with mining machinery, but it will be clear to those skilled 120 in the art that the particular type of conveyer disclosed will be found useful throughout a wide field and is not particularly limited to the mining industry, and it is therefore the intention of this invention to be limited only by the scope of the appended 125 claims.

Having thus described my invention, what is claimed as new and desired to be secured by U. S. Letters Patent is:

1. Conveying apparatus of the class described, in combination, a continuous belt conveyer, a framework therefor adapted to rest on a supporting surface, means to place said framework under longitudinal tension, a second continuous belt conveyer, a framework therefor, and means supporting said second framework, for longitudinal adjustment, above said first framework.
2. Conveying apparatus of the class described, in combination, a traveling conveyer having discharge mechanism at one end thereof, a framework for said conveyer adapted to slidably rest on a supporting surface, means to tension said framework longitudinally, a second continuous belt conveyer having charging means at one end thereof, a frame work therefor, and means supporting said second framework, for longitudinal adjustment, above said first framework whereby the distance between said discharging and said charging means may be adjusted without changing belt lengths.
3. Conveying apparatus of the class described, in combination, a framework including longitudinal members, conveyer troughing and idler rollers carried by said framework, means holding the forward end of said framework stationary and means at the rear end thereof to apply tension to said longitudinal frame members.
4. Conveying apparatus of the class described, in combination, a framework including longitudinal members, conveyer troughing and idler rollers carried by said framework, means holding the forward end of said framework stationary, means at the rear end thereof to apply tension to said longitudinal frame members and means on said longitudinal members to allow the extension of said framework.
5. Conveying apparatus of the class described, in combination, a lower framework including longitudinal members, means maintaining said members in parallel spaced relation, conveyer troughing and idler roll-

ers carried by said framework, means to place said longitudinal frame members under tension, a second conveyer framework similar to said first, and means on said second framework adapted to support it for longitudinal adjustment on the uppermost longitudinal members of the lower framework.

6. Conveying apparatus of the class described, in combination, a lower conveyer framework, an upper conveyer framework overlapping said lower framework, each framework including four longitudinal members parallel to each other and arranged at the four corners of a rectangle, brace members maintaining said spacing, belt rollers carried by said frameworks, means to place the longitudinal members of the lower framework under tension, and grooved rollers journaled on said upper framework and adapted to run on the upper longitudinal members of the lower framework to support the upper framework.

7. Conveying apparatus of the class described, in combination, a lower conveyer framework, an upper conveyer framework overlapping said lower framework at one end, movable charging apparatus attached to the opposite end of said upper framework, supporting means for said charging apparatus, and means on said upper framework adapted to roll on said lower framework whereby the amount of overlap of said conveyers may be adjusted.

8. Conveying apparatus of the class described, in combination, a lower conveyer framework, a belt therefor, a discharge mechanism at one end thereof, an upper conveyer framework partially overlapping said lower framework, a belt therefor, a movable means attached to the free end of said upper framework to move it, means on said movable means to drive said upper belt, means on said discharge mechanism to drive said lower belt in the same direction and means supporting said overlapping portion of said upper framework above said lower framework.

In testimony whereof I hereunto affix my signature.

FRANK D. ENNEY.
